US0D1093885S

(12) United States Design Patent (10) Patent No.: US D1,093,885 S
(45) Date of Patent: * Sep. 23, 2025

(54) HANDBAG

(71) Applicant: Bottega Veneta S.R.L., Montebello Vicentino (IT)

(72) Inventor: Matthieu Blazy, Milan (IT)

(73) Assignee: BOTTEGA VENETA S.R.L., Montebello Vicentino (IT)

() Term: 15 Years

(21) Appl. No.: 29/970,345

(22) Filed: Oct. 28, 2024

(30) Foreign Application Priority Data

Apr. 30, 2024 (EM) 015059382-0010

(51) LOC (15) Cl. 03-01

(52) U.S. Cl.

USPC D3/232

(58) Field of Classification Search

USPC D3/201, 217, 226, 230–233, 240–246, D3/249, 253, 285, 303, 318, 321–328;

D9/703–707, 710; D11/218–221

CPC A45F 3/02; A45C 13/08; A45C 13/18; A45C 1/024; A45C 3/06; A45C 15/00
